(57) **CLAIM**

We claim the ornamental design for a power adapter, substantially as shown and described.

DESCRIPTION

FIG. 1 is a perspective view of a power adapter in accordance with the present design.

FIG. 2 is a right side view for the power adapter shown in FIG. 1.

FIG. 3 is a rear view for the power adapter shown in FIG. 1.

FIG. 4 is a left side view for the power adapter shown in FIG. 1.

FIG. 5 is a front view for the power adapter shown in FIG. 1.

FIG. 6 is a top view for the power adapter shown in FIG. 1.

FIG. 7 is a bottom view for the power adapter shown in FIG. 1.

FIG. 8 is a perspective view for the power adapter with an adapter element removed in accordance with the present design.

FIG. 9 is a front view for the power adapter shown in FIG. 8; and,

FIG. 10 is a right side view for the power adapter shown in FIG. 8.

The adapter element is shown removed from the drawing views of FIGS. 8-10 for ease of illustration.
